UNITED STATES PATENT OFFICE.

MIRON GRAHAM TOUSLEY, OF ENGLEWOOD, ILLINOIS, ASSIGNOR TO
ARMENA PATRICK, OF SAME PLACE.

PORTABLE COAL AND COKE RESERVOIR.

SPECIFICATION forming part of Letters Patent No. 309,263, dated December 16, 1884.

Application filed July 6, 1883. (No model.)

To all whom it may concern:

Be it known that I, MIRON GRAHAM TOUSLEY, a citizen of the United States, residing at Englewood, in the county of Cook and State 5 of Illinois, have invented a new and useful Improvement in Portable Coal and Coke Reservoirs, for use with ordinary cooking stoves and ranges, of which the following is a specification.

10 The invention relates to a simpler and better method of constructing such portable coal and coke reservoirs than any heretofore known or used, such reservoir being adjustable to any ordinary cooking stove or range that has kettle-holes over the fire-box, and being removable at will. Heretofore such portable coal and coke reservoirs have either been made in combination with some specific pattern of stove or range or complicated with various 15 pieces and kinds of material in construction, thus presenting obstacles to their general adoption and use, notwithstanding the fact that the introduction of "water-fronts" into cooking stoves and ranges, the liability of 20 water-pipes to freeze, and the common necessities of many in rural districts make perpetual-burning fires in kitchens during the inclement months of winter an actual necessity.

As I have invented another form for the 25 construction of portable coal and coke reservoirs for which Letters Patent are desired, the device herein described will be designated as form A. Said portable coal and coke reservoir invented by me consists of an upright 30 tubular receptacle so shaped at the top as to receive an ordinary stove-lid for a cover, and furnished with a bail (or with handles) to lift it by, said tubular receptacle being similar in shape to an ordinary angled and perpendicular-sided stove-kettle, the larger diameter to 35 remain outside of the stove, the rectangular inward angle to rest on the top of the stove, and the smaller diameter to pass through a kettle-hole into the fire-box of the stove, but, 40 unlike such a kettle, has no bottom-plate, and through this open bottom coal and coke gravitate from the reservoir into the stove.

In the accompanying drawings, in which 45 similar letters of reference indicate like parts, Figure 1 is a perspective view of the device

embodiment my invention. Fig. 2 is a top view of the device with the lid or cover set aside. Fig. 3 is a vertical section of the same filled with coal, with the added outline of an ordinary cooking-stove, showing the manner of 55 its use. Fig. 4 is a perspective of the device combined with an ordinary cooking-stove.

In all the lettered figures of the drawings, A shows the upper part of said reservoir, with its greater diameter, that remains outside of the 60 stove. B shows the inward angle of the same, that sustains the weight of said reservoir on top of the stove and connects the larger and smaller diameters of said reservoir. C shows the smaller diameter of said reservoir, that 65 passes through the kettle-hole into the stove. D shows the open end of said reservoir, through which the coal or coke gravitates from said reservoir into the fire-box of the stove. E shows the top lid or cover of said reservoir. 70 F shows the bail or handles by which the said reservoir is lifted and carried. Said reservoir may be of any desired size or any relative length or proportion of parts, and its body made of cast-iron in a single piece. 75

The operation and application of the device areas follows: Said reservoir is inserted through a kettle-hole into the fire-box of the stove, when the fire is lighted, (see Figs. 3 and 4,) then filled with coal or coke in any quantity 80 desired, and the lid put on, and the flues of the stove may be closed or adjusted as may be deemed proper. To remove said reservoir, the ashes may be raked down and the fire and remaining fuel raked from under the reservoir into the fire-box with a hook, the reservoir set aside, and the lid replaced on the 85 stove.

Now, I do not claim the use of my portable coal and coke reservoir in the specially made 90 openings of formerly-patented cooking-stoves that combine coal reservoirs or magazines with their general parts in construction, as in Patents Nos. 129,379 and 129,466, of A. D. 1872; nor do I claim any of the irregular shapes or 95 bearings of the reservoirs or magazines of those patented stoves, which are very unlike the shapes and bearings of the device I claim. Nor do I claim the shape of the body of the reservoir when constructed with two separate 100

parts joined together with a simple slip-joint, and with the lower part slotted at the top to form bearings for the journal of an inside valve, as in Patent No. 44,612, of 1864, the construction of my device, on which I base my claim, being simpler and better adapted to its special use as a continuously-feeding reservoir or magazine of fuel, it having no slip-joint or journal-openings in its body and 10 no inside valve to obstruct the free gravitation of the fuel into the stove. Nor do I specially claim the bail or handles or the cover herein described, they being commonly-used attachments.

What I claim is—

The portable coal and coke reservoir, cast in a single piece, to be inserted through the kettle-hole of any ordinary cooking stove or range, consisting of an upper and lower part, each having the same axis, but of different 20 diameters, to form a shoulder for the support of the reservoir in the stove-hole, and provided with a cover and bail, substantially as described.

MIRON GRAHAM TOUSLEY.
